UNITED STATES PATENT OFFICE.

CORNELIUS A. BURNHAM, OF DAVISBURG, MICHIGAN.

DEVICE FOR TWISTING STAY-WIRES IN FENCES.

SPECIFICATION forming part of Letters Patent No. 568,660, dated September 29, 1896.

Application filed June 1, 1896. Serial No. 593,900. (No model.)

To all whom it may concern:

Be it known that I, CORNELIUS A. BURNHAM, a citizen of the United States, residing at Davisburg, in the county of Oakland and State of Michigan, have invented certain new and useful Improvements in Devices for Twisting Stay-Wires in Fences; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in fence-making, and especially to a tool for use in manufacturing a woven-fabric wire fence in the field after the line-wires have been secured to posts, and in carrying out my invention I provide a spacer having a series of studs set therein and temporarily held to the line-wires while the cross or stay wires are being twisted or woven in place by means of a suitable weaver.

To these ends and to such others as the invention may pertain the same consists, further, in the novel construction, combination, and adaptation of the parts, as will be hereinafter more fully described, and specifically defined in the appended claim.

I clearly illustrate my invention in the accompanying drawings, which, with the letters of reference marked thereon, form a part of this specification, and in which drawings similar letters of reference indicate like parts throughout the several views, in which—

Figure 1 is a side elevation of a section of a fence, showing the twist of the stay-wires, a portion showing the apparatus applied to the line-wires for twisting the same. Fig. 2 is an enlarged detail view of the spacer. Fig. 3 is a detail view of the weaver or tool for twisting the stay and line wires.

Reference now being had to the details of the drawings by letter, A A designate stringing-posts, which may be anchored down by cross-heads or in any other suitable way beneath the surface of the ground and may be stayed by braces and guy-ropes. To said posts are fastened by staples the line-wires B, the wires being first drawn taut to the end posts. Intermediate posts C are provided, to

which the line-wires are slidably held by means of staples, so as to allow same to be withdrawn when in the way of putting on the cross or stay wires. The line-wires thus in place, the spacer is fastened to two of the parallel line-wires. This spacer consists of the piece D, having two buttons E near the top and bottom of the piece and by which the said spacer may be held to the line-wires while the stay-wire is being twisted to the line-wires. A series of studs F, having slotted heads, is carried on the spacer. The first operation after the spacer is in place is to take a pair of pliers and make a loop in the end of the stay-wire, (said loop seen at G,) and the loop is then caught over the edge of the slot in the upper stud. The stay-wire, after being passed through the slot in the stud, is bent in a horizontal direction and parallel with the top line-wire. Now the weaver tool K, which has a recess M at one end and a slot N at its other end, is applied to the two wires thus disposed in the manner illustrated in the drawings, with the two wires inserted in the said slot and the line-wire resting in the recess M and the stay-wire being on the opposite side of the end of the weaver. The tool thus engaging the two wires is ready to be twisted, which is effected by turning the weaver to the left while looking down the fence being formed. After the twists are made in the wires the weaver is removed, the stay-wire bent diagonally and passed through the next stud, and the operation is repeated until the stay-wire is twisted to each of the line-wires, after which the spacer may be removed and a new series of twists made at regular intervals along the length of the fence. As the spacer approaches a line-post the staples may be withdrawn, so that there may be no hindrance to the twisting of the stay-wire. After passing the post the staples may be replaced and after the section of the fence is complete the staples may be tightened.

By the use of the weaver and spacer I am able to construct a fence which is thoroughly braced and strengthened, there being no possible lateral or longitudinal working loose of the wires, and a fence once constructed may be taken down and transported and set up, making a serviceable portable farm-fence.

It will be observed that the studs, which

are carried on the spacer, are adjustably held by means of a bolt on the side of the spacer-strip, and a series of apertures is provided in which the bolt may be passed in adjusting

5 the stud for different kinds of fences.

Having thus described my invention, what I claim to be new, and desire to secure by Letters Patent, is—

10 The device for twisting and making a fabric fence, which consists of the spacer having but-

tons by which the same is locked to the line-wires of the fence, and a series of slotted studs in said spacer, combined substantially as shown and described.

In testimony whereof I affix my signature 15 in presence of two witnesses.

CORNELIUS A. BURNHAM.
